UNITED STATES PATENT OFFICE.

WILLARD F. RICHARDS, OF DEPEW, NEW YORK, ASSIGNOR TO GOULD COUPLER COMPANY, OF NEW YORK, N. Y.

CAR-COUPING.

1,132,383.

Specification of Letters Patent. Patented Mar. 16, 1915.

Application filed October 14, 1912. Serial No. 725,575.

To all whom it may concern:

Be it known that I, WILLARD F. RICHARDS, a citizen of the United States, residing at Depew, in the county of Erie and State of New York, have invented a new and useful Improvement in Car-Couplers, of which the following is a specification.

This invention relates more particularly to improvements in railway car couplers, such as disclosed in Patent No. 1,015,052, granted Jan. 16, 1912, to E. M. Maw, assignor, which have a vertically-movable gravity-actuated lock for the horizontally swinging knuckle; and are provided with lock-set means for retaining the lock in the raised or released position when it is actuated to unlock the knuckle while the coupler is in connection with another coupler; and with a kicker or device which is actuated by the lock for throwing open the knuckle.

The object of the invention is to produce a car coupler having the advantageous features of said patented coupler, but the construction of which is improved in the several respects hereinafter specified and claimed for the purpose of making the coupler stronger and more durable; making it entirely reliable in action even after the parts have become worn and loose from usage; and eliminating as far as possible the labor and expense usually entailed in machining and grinding the parts when assembling them.

In the accompanying drawings consisting of two sheets: Figure 1 is a longitudinal sectional elevation of a car coupler embodying the invention, showing the locked position of the parts. Fig. 2 is a sectional plan thereof in line 2—2, Fig. 1. Fig. 3 is a transverse sectional elevation thereof. Fig. 4 is a transverse sectional elevation thereof showing the lock in its set or released position. Figs. 5 and 6 are, respectively, a sectional plan and transverse sectional elevation thereof showing the position of the parts when the knuckle is open. Fig. 7 is a sectional elevation showing a different operating device for the lock.

A represents the drawhead, B the horizontally swinging knuckle, and C the knuckle locking device of the coupler. The knuckle, as usual, is pivoted at one side of the head by a pin b and is provided with a tail b' which extends rearwardly into the head for engagement with the lock. The

knuckle tail has the usual lateral extension b² adapted to engage a part of the adjacent side wall of the head for relieving the knuckle pin from draft strains, and shoulders b³ adapted to strike the front wall 60 of the head to take the buffing shocks. In addition the lugs on the head through which the knuckle pin passes are provided, respectively, with bosses b⁴ b⁵. The upper boss b⁴ projects downwardly into a cavity b⁶ in the 65 top of the knuckle and the lower boss projects upwardly into a corresponding cavity in the bottom of the knuckle. The walls of these cavities are adapted to engage the inner sides of the bosses b⁴, b⁵ to resist side 70 strain in an outward direction on the knuckle pin in pulling, and to engage the outer sides of the bosses to resist side strain in an inward direction on the knuckle pin in buffing. The knuckle pin is thus relieved 75 from draft and buffing stresses in directions both longitudinally and laterally of the coupler, and a pin of smaller diameter than that ordinarily used can be employed. This enables the walls of the knuckle and its 80 hinge lugs surrounding the pin holes to be made thicker and stronger without increasing the dimensions of the coupler. Stop shoulders b⁷, formed on the bosses b⁴ b⁵, are adapted to be engaged by the ends of the 85 outer walls of the cavities b⁶ in the knuckle, as indicated in Fig. 2, to limit the outward swing of the knuckle. The knuckle is thus 90 prevented from striking and injuring the thin front edge of the side wall of the head. A shoulder or lug b⁸ is also formed in the 95 lower corner of the head adjacent to the knuckle tail which projects into a cavity b⁹ in the under side of the knuckle tail to further aid in relieving the knuckle pin 95 from draft strains.

The locking device C, as in said patented coupler, is arranged in the rear central portion of the coupler to slide vertically into and out of locking position between the tail 100 of the knuckle and the opposite side wall c of the head, and consists of a guide block C' and a combined locking and lock-set block C² pivoted to the guide block so as to swing thereon to a limited extent. The locking 105 block, instead of swinging longitudinally of the coupler, as in the patented coupler, swings crosswise thereof, and the guide block has a broad substantially rectangular upper portion from which the locking block 110

is suspended, and an upright rear portion c^2 which extends downwardly in rear of the locking block.

- The locking and guide blocks can be pivotally connected in any suitable way, as for instance, by a hinge lug on the locking block pivoted by a pin or rivet c^3 in a recess in the upper portion of the guide block, but the pivot is so located as to cause the lower 10 end of the locking block to swing by gravity over against the side wall c of the coupler head. The lock is confined and guided in its vertical movement between the front and rear walls of the head, the side wall c 15 and vertical ribs d d' in the head opposite the side wall c . The head has a horn or hollow top projection d^2 into which the lock is adapted to be lifted and this is suitably shaped to assist in guiding the lock. The 20 side wall c of the head retains the locking block upright when it is in its lower or locking position, but when the locking block is lifted clear of the knuckle tail in unlocking the knuckle, it will swing sidewise and 25 rest on a ledge or shoulder E on the side wall c , so as to retain the locking device in the released or lock-set position, as shown in Fig. 4. The knuckle can then be swung open. When the knuckle is swung open the 30 tail thereof is adapted to strike the rounded or cam-like lower inner corner e of the locking block, thereby swinging the block back to its upright position and disengaging it from the ledge E . The locking device when 35 thus released settles on the tail of the knuckle, riding thereon and being supported thereby while the knuckle is being opened and when it is in the open position. When the tail is moved from beneath the lock in 40 closing the knuckle, the lock drops between the knuckle tail and the side wall c and locks the knuckle. By arranging the locking block to swing sidewise of the coupler as described, the proper operation of the lock 45 is rendered much more certain and reliable, because if the knuckle should fail to disengage the lock from the ledge E when being opened, it will drag it off of the ledge when 50 it is being closed since that portion of the knuckle tail on which the lock rests moves in a direction almost directly away from the ledge E and it cannot pass by the depending inner corner e of the locking block 55 without dragging the block off of the ledge E .
- The inner upright face of the locking block and the cooperating face of the knuckle tail are preferably inclined slightly as shown, so that the locking block will wedge down between the tail and the side wall c enough to hold the knuckle firmly. In order to prevent the lock from wedging down so tightly as to cause it to stick and work hard in unlocking, the upper portion 60 of the guide block C' is made to project laterally beyond the locking block, as indi- 65

cated at f' , Fig. 3, so that it will strike the tail of the knuckle and limit the descent of the lock. The lock is thus supported by the tail of the knuckle when in its lower or locking position, with sufficient space between it and the floor of the head to prevent the accumulation of cinders, ice or other matter on the floor from preventing the descent of the lock to the correct locking position.

Means may be employed for operating the lock either from above or from below. As shown in Figs. 1-6, the operating means consists of a lifting rod G extending up through a hole g in the floor of the coupler head and connected at its upper end to the lock and at its lower end to a lever g' which is suitably fulcrumed below the head and has an arm g^2 extending upwardly at one side of the coupler and adapted to be connected to an operating rod (not shown) extending to the side of the car. Preferably, the lifting rod G has a knob or rounded portion g^3 at its upper end loosely fitting in a correspondingly shaped socket g^4 in the lower end of the upright rear portion of the guide block C' and retained in the socket by the locking block.

Fig. 7 shows an overhead operating device consisting of a link G' attached by an eye or loop h to the upper portion of the guide block and passing through a hole h' in the top of the head for connection with the usual operating shaft or rod (not shown) on the car. When the overhead operating device is used, the lifting rod G and lever g' are omitted, and when the latter are employed the link G' and eye h are omitted and the hole h' is closed by a suitable plug or cover h^2 .

I represents a knuckle opening device or kicker for throwing the knuckle to its open position. This kicker preferably consists of a lever pivoted as by a pin i in the upper portion of the coupler head so as to swing in a substantially vertical plane crosswise of the head. The kicker lever is weighted so that it normally hangs in the position shown in Fig. 3 with its lower end at the outer side of the tail of the knuckle and its rounded upper end overhanging the upper portion of the guide block. The lock can be raised and set in the released position shown in Fig. 4 without actuating the kicker I so as to permit the knuckle to be unlocked while in connection with another coupler. When, however, it is desired to throw the knuckle open the lock is lifted above the lock-set position and the upper portion of the guide block will then strike the kicker and swing it to the position shown in Fig. 6, thereby throwing open the knuckle. The pivot pin i for the kicker is adapted to be inserted before the knuckle is put in place, through the knuckle pin hole and a notch i' in the bottom of the upper boss b^4 . The kicker ar-

ranged as described works very easily and can be actuated with very little exertion to throw the knuckle fully open. It operates much easier than a kicker arranged to swing 5 on a vertical pivot and it will not get out of place and cause trouble as may possibly happen with a kicker pivoted on the lock.

The coupler described is very strong, durable and reliable in operation. The parts 10 are all large and of simple form and can be assembled and will operate properly in the condition in which they are taken from the molds with but little grinding and without machining. This materially facilitates the 15 assembling of the parts and reduces the cost of production of the coupler.

I claim as my invention:

1. In a car coupler, the combination with a drawhead, and a horizontally swinging 20 knuckle having a tail extending into the drawhead, of a locking device for the knuckle consisting of a guide block which is movable vertically within the drawhead below the top thereof and is held from tilting, and a locking block which is pivotally 25 suspended from said guide block to swing toward and from the side wall of the drawhead toward which the tail of the knuckle swings when opening the knuckle, a lifting 30 device co-operating with said guide block for operating said locking device, said side wall of the draw head being provided with a ledge on which said locking block is adapted to rest for supporting the knuckle in 35 raised position, said locking block when in its set position being raised by engagement with the knuckle tail during the opening movement thereof to disengage the block from said ledge and being frictionally 40 drawn away from said ledge during the closing movement of said knuckle, substantially as set forth.

2. In a car coupler, the combination with a drawhead, and a horizontally swinging 45 knuckle having a tail extending into the drawhead, of a locking device for the knuckle consisting of a guide block which is movable vertically in the drawhead and has an upright rear portion and an upper portion 50 extending forwardly from said rear portion, and a locking block which is pivotally suspended from said upper portion of the guide block in front of said rear portion thereof, and a seat in the drawhead onto which said 55 locking block is adapted to swing for supporting the locking device in raised position, substantially as set forth.

3. In a car coupler, the combination with a drawhead, and a horizontally swinging 60 knuckle having a tail extending into the drawhead, of a locking device for the knuckle consisting of a guide block which is movable vertically in the drawhead and has an upright rear portion and an upper portion 65 extending forwardly from said rear portion,

and a locking block which is pivotally suspended from said upper portion of the guide block in front of said rear portion thereof, a seat in the drawhead onto which said locking block is adapted to swing for supporting the locking device in raised position, and an operating device for the locking device which is located at the lower portion of the coupler and is connected with said upright rear portion of the guide block, substantially 70 as set forth.

4. In a car coupler, the combination with a drawhead, and a horizontally swinging knuckle having a tail extending into the drawhead, of a locking device for the knuckle consisting of a guide block which is movable vertically in the drawhead and a combined locking and lock set block which is pivoted to said guide block, and a seat onto which said locking and lock set block is 80 adapted to swing for supporting the locking device in raised position, said locking and lock set block being adapted to wedge in between the knuckle tail and part of the drawhead for locking the knuckle, and said guide block having a part adapted to engage the knuckle for limiting said wedging action of the locking and lock set block, substantially 85 as set forth.

5. In a car coupler, the combination with a drawhead, and a horizontally swinging knuckle having a tail extending into the drawhead, of a locking device for the knuckle consisting of a guide block which is movable vertically in the drawhead and has an 90 upright portion and an upper portion extending laterally from said upright portion, and a locking block which is pivotally suspended from said upper portion of the guide block, and an operating device for the 95 locking device which is located at the lower portion of the coupler and extends upwardly at one side of the locking block and engages the upwardly extending portion of said 100 guide block, substantially as set forth.

6. In a car coupler, the combination with a drawhead, and a horizontally swinging knuckle having a tail extending into the drawhead, of a locking device for the knuckle consisting of a guide block which is movable vertically in the drawhead and has an upright portion and an upper portion 115 extending laterally from said upright portion, and a locking block which is pivotally suspended from said upper portion of the guide 120 block, and an operating device for the locking device including a rod extending at one side of the locking block and having an enlarged portion entering a socket in said 125 upright portion of the guide block.

7. In a car coupler, the combination with a drawhead, and a horizontally swinging knuckle having a tail extending into the drawhead, of a locking device for the knuckle consisting of a guide block which is mov- 130

able vertically in the drawhead and has an upright portion and an upper portion extending laterally from said upright portion, and a locking block which is pivotally suspended from said upper portion of the guide block, and an operating device for the locking device including a rod extending at one side of the locking block and having a portion entering a recess in said upright portion 10 of the guide block and held in place therein by said locking block.

8. In a car coupler, the combination with a drawhead, and a horizontally-swinging knuckle having a tail extending into the 15 drawhead, of a locking device for the knuckle consisting of a guide block which is movable vertically within the drawhead below the top thereof, said drawhead having an in-

ternal guideway in which the guide block is movable vertically and is held from tilting, and a locking block which is pivotally suspended from said guide block to swing crosswise in the drawhead, and a stationary seat in the drawhead onto which said locking block is adapted to swing for supporting the locking device in raised position, said seat being located at that side of the drawhead toward which the tail of the knuckle swings when opening the knuckle, substantially as set forth. 30

Witness my hand this 7th day of October, 1912.
